UNITED STATES PATENT OFFICE.

STEPHEN DE ORLOW, OF DETROIT, MICHIGAN.

HOOD FASTENER.

Application filed September 17, 1925. Serial No. 56,853.

This invention relates to hood fasteners of that type used at the side walls of an engine hood or cover for retaining the hood or cover in a closed position, yet permitting 5 of easy access being had to the interior of the hood by simply raising the side walls thereof.

The primary object of my invention is to provide a hood fastener consisting of comparatively few parts that may be cut or stamped and pressed from sheet metal with the parts of such configuration as to be easily and quickly assembled relative to a hood and its support. A further object of 15 this invention is to provide a hood fastener including an inside bracket, a latch member movably supported by the bracket and guided by the hood wall so that it may be shifted relative to a keeper inside the hood, and a 20 handle member connected to the latch member and extending through the hood wall and adapted to fulcrum against the bracket so that the latch member may be shifted relative to its keeper.

25 Other objects and advantages are gained by my hood fastener which will now be described by aid of the drawings, wherein

Figure 1 is a vertical sectional view of a portion of a hood provided with a fastener shown as holding a hood wall in a closed 30 position;

Fig. 2 is a view of the inner side of the hood wall provided with a fastener;

Fig. 3 is a horizontal sectional view taken 35 on the line III—III of Fig. 1;

Fig. 4 is a view similar to Fig. 1 showing the latch mechanism shifted for opening the hood;

Fig. 5 is a perspective view of a bracket 40 carried by the hood wall;

Fig. 6 is a similar view of a handle member, and

Fig. 7 is a similar view of a fulcrum abutment for the handle member.

45 In the drawings, the reference numeral 1 denotes a portion of a hood wall having a vertical handle slot 2. The lower edge of the hood wall is adapted, when closed to engage a stop flange or member 3 supported 50 from a vehicle frame or chassis 4, which is provided with a U-bolt keeper 5 within the hood.

Attached to the inner face of the hood wall 1 by rivets 6 is an angle bracket 7 having its side edges formed with stiffening flanges 8. The upper or vertical portion of a

bracket 7 is pressed outwardly to provide a guide housing 9 having a longitudinal slot 10 with the lower end of the slot enlarged, as at 11.

60 The lower or horizontal portion of the bracket 7 is provided with an up-struck spring retainer 12 and at the angle of the bracket is an opening 13 and a communicating slot 14.

65 Mounted on the lower or horizontal portion of the bracket 7 and secured thereto by rivets 15 are the apertured ears 16 of an angularly disposed fulcrum abutment 17 which is located at the closed end of the slot 70 14 and extends upwardly at an angle to said bracket.

75 The reference numeral 18 denotes a latch member which has its lower end somewhat hook shaped, as at 19 and provided with a keeper engaging lip 20. The upper end of the latch is also somewhat hook shaped, as at 21 and is formed with a spring retainer 22 adapted to cooperate with the spring retainer 12 of the bracket in retaining a coiled 80 expansion spring 23 in place so that its expansive force against the upper end of the latch member will hold the lower end thereof in engagement with the keeper 5. The upper end of the latch member is also formed with a guide lug 24 twisted to afford a head 85 25 which is placed through the enlarged end 11 of the slot 10 to ride in the guide housing 9 and retain the latch member at all times in engagement with the hood wall 1, 90 yet permit of said latch member being tilted or otherwise shifted relative to the hood wall.

95 The reference numeral 26 denotes a handle member slidable in the slot 2 of the hood wall 1 with the outer end of the handle member fashioned to provide a hook shaped handle 27. The inner end of the handle member 21 is formed with apertured ears 28 and a channel member 29, such apertured 100 ears being pivotally connected to the lower portion of the latch member 18 by a rivet 30 or other pivotal means. The channel member 29 embraces the latch member 18 and presents a flat face 30 adapted for engagement with the flat face 31 of the abutment 17.

105 The slot 2 and the opening 13 provide clearance for the handle member 26 and the walls of the slot 14 are adapted to guide the channel member 29 with the latch member 18 110 therein. As shown in Figs. 1 and 2, the flat

faces of the channel member 29 and the abutment 17 are in engagement with each other; the handle member 26 supported substantially horizontal, and the lip 20 in engagement with the keeper 5 with the hood wall 1 against the stop flange 3 and in a closed position.

When the handle 27 is pulled upon, as when leaving the wall 1, the upper end of the channel member 29 fulcrums against the abutment 31 and as the handle member 26 is tilted the lower hook shaped end 19 of the latch member is swung towards the hood wall 1 thus moving the lip 20 out of engagement with the keeper 5. As this is accomplished the upper end of the latch member 18 is tilted away from the hood wall 1 and the spring 23 placed under additional tension. After the latch member clears the keeper 5 the expansive force of the spring 23 will restore the latch member 18 and the handle member 26 to normal positions relative to each other, but raised relative to the bracket 7 and the abutment 17. The channel member 29 will be held snug against the abutment and the guide housing will limit the upward movement of the handle member as well as the latch member, retaining these two members in position so that the handle member can be gripped for replacing the hood cover. The latch member will readily ride into engagement with the keeper and the manner in which the parts are assembled, eliminates rattling of such parts or any accidental displacement thereof.

I attach considerable importance to the fact that a hood equipped with my fasteners, for instance two, obviates the necessity of using any other handles on the hood wall, for the reason that my handle members can be gripped for moving the hood wall in a natural way. Some fasteners now in use require a hood wall to be manipulated with one hand while a latch is manipulated with the other hand, but in my arrangement the hood wall can be manipulated by virtue of the fasteners. I would also direct attention to the angularity of the latch members relative to the hood wall and the fact that these latch members are loosely connected to the hood wall and have an angular engagement with the keepers, with means above the keepers for establishing a connection between the keepers and the latch members. The means permits of the latch members being tilted, during a latching or unlatching operation and the expansive force of said means, through the medium of the latch members, tends to pull the hood wall inwardly and downwardly. There is always a clamping action of the hood wall against the stop flange, and a snap action of the latch mem-

bers relative to the keepers. In opening the hood wall the natural movement is to pull upwardly and outwardly and such force on the handle members removes the latch members from the keepers. In closing the hood wall the natural movement is downwardly and inwardly and pressure on the handle members, incident to closing the hood wall, lowers the latch members for engagement under the keepers.

It is thought that the operation and utility of the fastener will be apparent without further description and that any number of fasteners may be used in connection with hood walls or other closure members.

What I claim is:—

1. In a hood fastener, the combination with a hood wall and a keeper within the hood, of a bracket carried by the inner face of said hood wall and provided with a spring retainer, a latch member having its upper end guided by said bracket, a spring retainer on the upper end of said latch member, a lip on the lower end of said latch member adapted to engage said keeper, a spring on a portion of said bracket having its end convolutions extending from said spring retainers to retain said latch member in engagement with said keeper, and a handle member extending through said hood wall and pivotally connected to said latch member and adapted to fulcrum on said bracket between said spring and said hood wall to shift said latch member out of engagement with said keeper.

2. A hood fastener as called for in claim 1, wherein said bracket has a fulcrum abutment with which said handle member has an edge engagement for shifting said latch member.

3. In a hood fastener wherein a hood wall is adapted to be held relative to a keeper inside the hood; a latch mechanism including a bracket on the inner face of said hood wall, a flat face abutment on said bracket, a latch member extending through said bracket and supported therefrom for engagement with said keeper, and a handle member pivotally connected to said latch member and extending through said hood wall, said handle member having a flat face for engagement with the abutment of said bracket so that said handle member is held normally horizontal, the engagement between said bracket and handle member causing the lower end of said latch member to be shifted towards said hood wall and the upper end of said latch member shifted away from said hood wall when said handle member is raised incident to opening the hood.

In testimony whereof I affix my signature.

STEPHEN DE ORLOW.
